DESIGN FOR A FORK OR SIMILAR ARTICLE

Milton Bernstein, Brooklyn, N. Y.

Application July 27, 1938, Serial No. 78,785

Term of patent 3½ years

To all whom it may concern:

Be it known that I, Milton Bernstein, a citizen of the United States, residing in the Borough of Brooklyn, county of Kings, city and State of New York, have invented a new, original, and ornamental Design for a Fork or Similar Article, of which the following is a specification, reference being had to the accompanying drawing, forming a part thereof, in which:

Fig. 1 is a front elevational view of a fork or similar article embodying my new design; and

Fig. 2 is a side elevation thereof.

In the drawing, a fork is shown in broken lines in association with a handle embodying my new design. The handle is, however, adapted for use with articles of tableware and flatware generally, including knives, forks, spoons, and the like.

I claim:

The ornamental design for a fork or similar article, as shown and described.

MILTON BERNSTEIN.
